UNITED STATES PATENT OFFICE.

HARRY P. SICKELS, OF ROCHESTER, NEW YORK.

DESIGN FOR A MAIL-BOX.

49,163.

Patented June 6, 1916.

Application filed April 5, 1915. Serial No. 19,368. Term of patent 14 years.

To all whom it may concern:

Be it known that I, HARRY P. SICKELS, a citizen of the United States, residing at Rochester, in the county of Monroe and State of New York, have invented a new, original, and ornamental Design for Mail-Boxes, of which the following is a specification, and of which the accompanying drawing is a representation.

Figure 1 is a front elevation of a mail box, showing my new design, and Fig. 2 is a side elevation.

I claim:

The ornamental design for a mail box, as shown.

HARRY P. SICKELS.
